UNITED STATES PATENT OFFICE.

MICHAEL STOJAK, OF BROOKLYN, NEW YORK.

DESIGN FOR A PICTURE FRAME.

Application filed June 13, 1922. Serial No. 2,656. Term of patent 3½ years.

To all whom it may concern:

Be it known that I, MICHAEL STOJAK, a citizen of Poland, and resident of Brooklyn, county of Kings, and State of New York, have invented a new, original, and ornamental Design for a Picture Frame, of which the following is a specification, reference being had to the accompanying drawing, forming part thereof.

Fig. 1 is a face view illustrating a corner of a picture frame embodying my new design, and

Fig. 2 is a partial inside edge view, looking in the direction of the arrow in Fig. 1.

The detailed showing of the design illustrated in the left hand corner of the frame extends throughout the entire frame.

I claim:

The ornamental design for a picture frame, substantially as shown and described.

Signed at New York city, in the county and State of New York, this 12th day of June, 1922.

MICHAEL STOJAK.
